DESIGN FOR A BACON SLICING MACHINE COVER

Edward A. Schiewe, Park Ridge, Ill.

Application June 3, 1939, Serial No. 85,335

Term of patent 3½ years

To all whom it may concern:

Be it known that I, Edward A. Schiewe, a citizen of the United States, residing at Park Ridge, in the county of Cook and State of Illinois, have invented a new, original, and ornamental Design for a Bacon Slicing Machine Cover, of which the following is a specification, reference being had to the accompanying drawings, forming a part thereof.

Figure 1 is a perspective view of a bacon slicing machine cover showing my new design.

Figure 2 is a side view of the bacon slicing machine cover shown in Figure 1, on a reduced scale.

Figure 3 is a side view of the bacon slicing machine cover, likewise on a reduced scale, and showing the opposite side of the cover shown in Figure 1.

Figure 4 is an end view of the charging end of the bacon slicing machine cover, being the right hand end of the cover shown in Figure 1.

Figure 5 is an end view of the discharging end of the bacon slicing machine cover, being the left hand end of the cover shown in Figure 1.

I claim:

The ornamental design for a bacon slicing machine cover, as shown.

EDWARD A. SCHIEWE.
